COMBINATION LOCK

Carl Paganini, Stuttgart, Germany

Application April 9, 1951, Serial No. 219,909

Claims priority, application Germany
May 25, 1950

8 Claims. (Cl. 70—312)

1

This invention relates to a combination lock for securing objects of various kinds such as, for example, brief cases, ladies' handbags, jacket zippers etc., and the invention has for its object to provide a safety lock of simple construction, the bolt of which can be released only by setting two or more dials to two or more predetermined letters or figures.

It is a primary object of the present invention to overcome the disadvantages of known locks by providing a lock which is distinguished by its small size, by its great resistance to wear, by its light weight and its effective fastening.

The new lock provided by the present invention consists principally of an upper part containing the setting mechanism and of a separate lower keeper part with the lug. The upper part is formed by the lock casing and by the cover plate and these two parts are riveted together. Freely revolving sleeves are arranged on the rivet shanks. Rigidly secured to the sleeves are the dials with the inscribed letters or figures and another member having resilient sections, the edges of which are bent up so as to engage the lug in the lower lock part. For securing the keeper the upper part is placed upon the keeper, as slight pressure is exerted upon the upper part the resilient members with their bent up edges engage the noses of the lug; thus securing a safe fastening.

At definite dial markings there are no bent up edges on the resilient section belonging thereto. When the dials are turned until these particular markings are directly adjacent each other then the bent up edges do not engage the noses and thus the bolt is released.

The accompanying drawings illustrate one embodiment of the invention. On the drawings:

Fig. 1 is an enlarged top plan view of the combination lock provided by the invention,

Fig. 2 is an enlarged longitudinal sectional view through the lock, showing some of the parts in elevation,

Fig. 3 is an enlarged side elevation of the lower part of the lock, and

Fig. 4 is an enlarged transverse sectional view through the lock, showing some of the parts in elevation.

The combination lock provided by the invention consists of an upper part containing setting mechanism *e*, *f*, *g*, and of a separate lower part or keeper comprising plate *m* and lug *n*. The upper part is formed of a casing *a* and a cover plate *b* and a setting mechanism is arranged between these two parts. The casing *a*

2

and the cover plate *b* are rigidly secured to each other by means of rivets *c*. Arranged to be freely movable clockwise and counter-clockwise on the rivet shanks *c* are sleeves *d*. Rigidly secured to the upper portion of the sleeves *d* are dials *e* and bell-shaped members *f* provided with bent up flanges *g*. The dials *e* are inscribed with letters *l* or figures which are set to be visible in the windows *h* arranged in the part *a*, for manipulating the lock. The perimeter of the members *f*, and particularly the flanges *g* are divided, by means of narrow radial slots *i*, for example, into resilient locking sections which are still connected at the top and correspond to the number of letters inscribed on the disk *e*. These slots *i* cause the sections situated between two adjacent slots *i* to be resilient so as to move inwardly when pressure is exerted upon them (see Fig. 2) and to spring back again whenever there is no pressure. The transverse sides of the casing *a* are provided with slots and the knurled edges of the dials *e* project therethrough permitting the dials *e* to be turned respectively to be set by these projecting edges. A lug *n* provided with two noses *o* is rigidly secured on the face plate *m*. The cover plate *b* of the upper lock part is provided with a rectangular hole *p* adapted to receive the lug *n*. On connecting the upper part *a*, *b* with the lower part *m*, *n*, the lug *n* is put into the hole *p*. In the center of the hole *p* there is a transverse member *s* which engages the notch *r* of the lug *n* on connecting the lock parts *a*, *b* and *m*, *n*.

In order to secure the lug the keeper of the lock is placed upon the upper part, this puts the lug *n* into the hole *p* and the lug *n* moves the resilient sections of the members *f* so far inwards until the bent up edges *g* spring back and engage the noses *o* of the lug *n*. Thus the upper and lower lock parts are securely locked together.

The lug of the lock provided by the invention can be released only by turning both dials *e* until they are in a predetermined position as to each other. In order to render such releasing by means of dials possible, some of the bent up edges *g* between two slots *i* on the members *f* have been removed at *k*, according to the drawing, for example, on those sections of the members *f* associated with the letters *W* and *B* (see Fig. 1). If the dials *e* are now so manipulated that the letters *W* and *B* appear in the windows *h*, then the upper part of the lock is released from the lower part, whereas in all other positions of the dials *e* the lock cannot be released. Consequently, in the present instance

the lock can be released only with the combination W and B. Through the above described spacing of letters or figures on the dials *e*, which serves as an example, provision is made for 64 combinations, but there is only one combination to unlock, that is, the lug is not released until after the dials *e* have been so manipulated as to combine, for example, at least two letters or figures. By changing the position of the letters or figures another combination can be formed with each change.

The new lock provided by the invention may also be formed to have more than two dials *e*, whereby the number of combinations may be substantially increased.

The new lock is particularly well adapted as fastening for brief cases, ladies' handbags, jackets, zippers and also for luggage, laundry bags, lock-up diaries and likewise for vehicles, for example, automobiles, bicycles, etc. If the new lock, for example, is to be used with a zipper, then the plate *m* is secured to the end of the zipper by means of riveting, sewing or the like. The plate *b* of the upper lock part is provided with extensions *q* in the form of eyes (Fig. 1). These eyes *q* are connected to the zipper slide so that the upper lock part can be used as a zipper pull. Upon closing of the zipper the upper and lower lock parts are pushed together and are thus locked as previously described. In order to use the new lock as a fastening for a brief case, the upper lock part is fastened to the flap and the keeper part to the case itself.

The new lock may be made of any suitable material such as metal.

What is claimed is:

1. A combination lock comprising, in combination, a casing having a wall formed with at least one opening; a detachable keeper member including a lug formed with a recess and projecting into said opening in said casing; at least one setting means mounted in said casing and rotatable to a plurality of positions, said setting means including a radially projecting flange formed with a cut-out corresponding to one of said positions, and being composed of a plurality of resilient locking sections corresponding to each of the other of said positions, each of said locking sections consecutively passing said opening during rotation of said setting means projecting into said recess of said lug and engaging and holding said lug and thereby locking said keeper member to said casing, said keeper member being free to be detached only in the position of said setting means in which said cut-out registers with said opening, said resilient sections, when aligned with said opening, permitting insertion of said lug into said opening by resiliently giving; indicating means secured to said setting means and indicating the position of the same; and manually operated means connected to said setting means for rotating the same.

2. A combination lock comprising, in combination, a casing having a wall formed with at least one opening; a detachable keeper member located adjacent to said wall and including a lug formed with at least two oppositely arranged lateral recesses, and projecting into said opening in said casing substantially normal to said wall; at least two setting means rotatably mounted in said casing, one on each side of said opening and having parallel axes of rotation extending normal to said wall, each of said setting means being rotatable independently of the other setting means to a plurality of positions, each setting means in-

cluding a substantially radially projecting flange formed with a cut-out corresponding to one of said positions of the corresponding setting means, each of said flanges being composed of a plurality of resilient locking sections corresponding to each of the other of said positions and being separated by radial slots, each of said locking sections consecutively passing said opening during rotation of the corresponding setting means projecting into one of said recesses of said lug, and engaging and holding said lug and thereby locking said keeper member to said casing, said keeper member being free to be detached when said two setting means are in a position thereof in which the cut-outs of both setting means register with said opening, said resilient sections, when aligned with said opening, permitting insertion of said lug into said opening by resiliently giving and sliding on said lug until snapping into said recesses therein; two indicating means, each indicating means indicating the position of one of said setting means; and two manually operated means, each manually operated means connected to one of said setting means for rotating the same.

3. A combination lock comprising, in combination, a casing having a wall formed with at least one opening; a detachable keeper member located adjacent to said wall and including a lug formed with at least two oppositely arranged lateral recesses, and projecting into said opening in said casing substantially normal to said wall; at least two setting means rotatably mounted in said casing, one on each side of said opening and having parallel axes of rotation extending normal to said wall, each of said setting means being rotatable independently of the other setting means to a plurality of positions, each setting means including a bell-shaped member being formed with a cut-out corresponding to one of said positions of the corresponding setting means, each bell-shaped member being partly composed of a plurality of resilient locking sections corresponding to each of the other of said positions and being separated by slots and being bent out and away from said wall, each of said locking sections consecutively passing said opening during rotation of the corresponding setting means projecting into one of said recesses of said lug, and engaging and holding said lug and thereby locking said keeper member to said casing, said keeper member being free to be detached when said two setting means are in a position thereof in which the cut-outs of both setting means register with said opening, said resilient sections, when aligned with said opening, permitting insertion of said lug into said opening by resiliently giving and sliding on said lug until snapping into said recesses therein; two indicating means, each indicating means indicating the position of one of said setting means; and two manually operated means, each manually operated means connected to one of said setting means for rotating the same.

4. A combination lock comprising, in combination, a casing open on one side thereof; a wall formed with at least one opening and located on said open side of said casing; at least two spaced parallel pins extending normal to said wall, one located on each side of said opening therein, each pin being secured at one end to said wall and at the other end to said casing so as to secure said wall to said casing; a detachable keeper member located adjacent to said wall and including a lug formed with at least two oppositely arranged lateral recesses, and projecting into said opening in said casing substantially

normal to said wall; at least two setting means mounted in said casing, one on each of said pins and being rotatable thereon, each of said setting means being rotatable independently of the other setting means to a plurality of positions, each setting means including a bell-shaped member being formed with a cut-out corresponding to one of said positions of the corresponding setting means, each bell-shaped member being partly composed of a plurality of resilient locking sections corresponding to each of the other of said positions and being separated by slots and being bent out and away from said wall, each of said locking sections consecutively passing said opening during rotation of the corresponding setting means projecting into one of said recesses of said lug, and engaging and holding said lug and thereby locking said keeper member to said casing, said keeper member being free to be detached when said two setting means are in a position thereof in which the cut-outs of both setting means register with said opening, said resilient sections, when aligned with said opening, permitting insertion of said lug into said opening by resiliently giving and sliding on said lug until snapping into said recesses therein; two indicating means, each indicating means indicating the position of one of said setting means; and two manually operated means, each manually operated means connected to one of said setting means for rotating the same.

5. A combination lock comprising, in combination, a casing having a wall formed with at least one opening; an elongated bridge member secured at the ends thereof to the inside of said wall, and having a center portion extending across said opening so as to divide said opening into two symmetrical portions; a detachable keeper member located adjacent to said wall and including a lug formed with a notch in the front end face thereof and with at least two oppositely arranged lateral recesses, and projecting into said opening in said casing substantially normal to said wall with said bridge member passing transversely through said notch and engaging said lug; at least two setting means rotatably mounted in said casing, one on each side of said opening and having parallel axes of rotation extending normal to said wall, each of said setting means being rotatable independently of the other setting means to a plurality of positions, each setting means including a substantially radially projecting flange formed with a cut-out corresponding to one of said positions of the corresponding setting means, each of said flanges being composed of a plurality of resilient locking sections corresponding to each of the other of said positions and being separated by radial slots, each of said locking sections consecutively passing said opening during rotation of the corresponding setting means projecting into one of said recesses of said lug, and engaging and holding said lug and thereby locking said keeper member to said casing, said keeper member being free to be detached when said two setting means are in a position thereof in which the cut-outs of both setting means register with said opening, said resilient sections, when aligned with said opening, permitting insertion of said lug into said opening by resiliently giving and sliding on said lug until snapping into said recesses therein; two indicating means, each indicating means indicating the position of one of said setting means; and two manually operated means, each manual-

ly operated means connected to one of said setting means for rotating the same.

6. A combination lock comprising, in combination, a casing having a wall formed with at least one opening; a detachable keeper member located adjacent to said wall and including a lug formed with at least two oppositely arranged lateral recesses, and projecting into said opening in said casing substantially normal to said wall; at least two setting means rotatably mounted in said casing, one on each side on both sides of said opening and having parallel axes of rotation extending normal to said wall, each of said setting means being rotatable independently of the other setting means to a plurality of positions, each setting means including a substantially radially projecting flange formed with a cut-out corresponding to one of said positions of the corresponding setting means, each of said flanges having a plurality of resilient locking sections corresponding to each of the other of said positions and being separated by radial slots, each of said locking sections consecutively passing said opening during rotation of the corresponding setting means projecting into one of said recesses of said lug, and engaging and holding said lug and thereby locking said keeper member to said casing, said keeper member being free to be detached when said two setting means are in a position thereof in which the cut-outs of both setting means register with said opening, said resilient sections, when aligned with said opening, permitting insertion of said lug into said opening by resiliently giving and sliding on said lug until snapping into said recesses therein; two manually operated dial means, each dial means secured to one of said setting means and rotating with the same, each of said dial means being provided with a number of indicia, each indicium corresponding to one position of the corresponding dial means; and fixed indicating means on said casing cooperating with said dial means to indicate the position of each of said setting means.

7. A combination lock according to claim 6 wherein each of said dial means is located within said casing, said casing being formed with slots through which said indicating dial means projects to the outside so as to be manually rotated; and wherein said fixed indicating means are the edges of apertures formed in said casing and permitting viewing of one of said indicia on each of said dial means.

8. A combination lock comprising, in combination, a casing having a wall formed with at least one opening; an elongated bridge member secured at the ends thereof to the inside of said wall, and having a center portion extending across said opening so as to divide said opening into two symmetrical portions; a detachable keeper member located adjacent to said wall and including a lug formed with a notch in the front end face thereof and with at least two oppositely arranged lateral recesses, and projecting into said opening in said casing substantially normal to said wall with said bridge member passing transversely through said notch and engaging said lug; at least two setting means rotatably mounted in said casing, one on each side of said opening and having parallel axes of rotation extending normal to said wall, each of said setting means being rotatable independently of the other setting means to a plurality of positions, each setting means including a bell-shaped member being formed with a cut-out corresponding to one of said positions of the corresponding setting means,

each bell-shaped member being partly composed of a plurality of resilient locking sections corresponding to each of the other of said positions and being separated by slots and being bent out and away from said wall, each of said locking sections consecutively passing said opening during rotation of the corresponding setting means projecting into one of said recesses of said lug, and engaging and holding said lug and thereby locking said keeper member to said casing, said keeper member being free to be detached when said two setting means are in a position thereof in which the cut-outs of both setting means register with said opening, said resilient sections, when aligned with said opening, permitting insertion of said lug into said opening by resiliently giving and sliding on said lug until snapping into said recesses therein; two manually operated dial

10

15

means, each dial means secured to one of said setting means and rotating with the same, each of said dial means being provided with a number of indicia, each indicium corresponding to one position of the corresponding dial means; and fixed indicating means on said casing cooperating with said dial means to indicate the position of each of said setting means.
